OIL BURNER

William O. Behrens, Harvey, Ill.

Application July 11, 1936, Serial No. 90,232

6 Claims. (Cl. 158—77)

The present invention relates to improvements in oil burners.

Various objects of the invention are to provide a new and improved oil burner which is compact, simple and inexpensive in construction, which is adapted for ready assembly and ease in dismantling, which is easily cleaned, and which has a low cost of installation and maintenance and simplifies the furnace brick work by not requiring separate secondary air inlets nor complicated interlocks.

Another object of the invention is to provide a novel oil or liquid fuel burner in which all of the air is supplied by forced draft, and more specifically in which primary air is supplied by a high pressure fan, and in which a low pressure fan supplies secondary air and also the air for the high pressure fan.

A further object is to provide two fans discharging in series and parallel, and driven jointly from a common source, the first fan having a relatively large capacity and a low pressure output, and the second fan having a relatively small capacity and high pressure output.

Other objects of the invention are to provide a novel oil burner which is efficient in operation, which effects a thorough mixing of air and fuel, and in which the low pressure air is controlled with the fuel supply, so that the fire is never lazy and smoky and the efficiency does not vary with the draft.

Further objects and advantages will become apparent as the description proceeds.

In the accompanying drawing, Figure 1 is a longitudinal sectional view of an oil burner embodying the features of my invention.

Figs. 2 and 3 are transverse sectional views taken respectively along lines 2—2 and 3—3 of Fig. 1.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the drawing, the burner constituting the exemplary embodiment of the invention, is adapted to discharge a stream of air and finely atomized fuel oil into a furnace. In the present instance, a fragment of the furnace is illustrated, the furnace having

a refractory wall 4 formed with a burner opening 5. A burner front plate 6 is secured against the exterior of the wall 4, and has an opening 7 in registration with the opening 5.

The burner has a low pressure air nozzle 8 extending into the opening 5. Preferably, the nozzle 8 is in the shape of a Venturi tube. The peripheral wall of the opening 5 is shaped to conform to the nozzle 8. An outer peripheral flange 9 on the inlet end of the nozzle 8 is securely bolted to the plate 6.

The nozzle 8 opens from a housing 10 enclosing a low pressure air fan or blower 11, and having a cover 12. The housing is suitably supported, with the cover 12 in position against the flange 9. The cover 12 is formed with a flange 13 tapered internally to provide a continuation of the nozzle 8, and the portion thereof circumscribed by the flange 13 constitutes a radially disposed plate member 14 terminating in a concentric inner ring 15. A rotary damper or shutter member 16 is disposed against the member 14, and is adjustable by means of a rod 17 pivotally connected to one side, as illustrated in Fig. 2, and extending out of the housing 10. The members 14 and 16 have peripheral spaced openings 14a and 16a movable into various degrees of registration to regulate the amount of air discharging through the nozzle 8.

Extending coaxially through the nozzle 8 is a high pressure air nozzle 18. This nozzle is tapered so that the intervening annular air space between the nozzles is of gradually increasing flow area. The nozzle 18 is mounted on the end of a tube 19 which extends through and is supported in the ring 15, and which constitutes the axial outlet of a housing 20 enclosing a high pressure air fan or blower 21. The tube 19 also supports the damper member 16.

The blower 21 may be of any suitable form, and in the present instance has an axial inlet taking low pressure air through an axial opening 22 in the housing 20 from the housing 10, and has a peripheral discharge. A circular baffle or guide plate 23 is mounted substantially in the center of the housing 20, and serves to direct air from the periphery inwardly to the tube 19. Likewise, the low pressure blower 11, although smaller in diameter than the blower 21, has an axial inlet and a peripheral discharge into the housing 10. A baffle or guide plate 24 is disposed between the blowers 11 and 21 to direct air from the housing 10 to the inlet opening 22 of the housing 20.

Secured to and closing one side of the housing 10 is a cylindrical housing 25 having a plu-

55

rality of air inlets 26, 27 and 28 opening from the atmosphere. The inner end wall of the housing 25 is formed with an axial outlet opening 29 which communicates with the housing 10, and which is in direct registration and closely inter-fitting relation with the inlet of the blower 11.

The two blowers 11 and 21 are mounted coaxially on a common drive shaft 30 which is journalled in spaced bearings 31 and 32 in opposed walls of a gear chamber 33 within the housing 25. The outer end of the shaft 30 is also supported in a sleeve 34 on a valve body 35 mounted on the outer end of the housing 25. Any suitable means may be provided for driving the shaft 30, and in the present instance this means comprises an electric motor 36 having a casing 37 built into the outer end of the housing 25 between the gear chamber 33 and the valve body 35.

Mounted for rotation coaxially within the high pressure air nozzle 18 and coacting therewith to define a tapered annular air passage is a substantially cylindrical atomizing cup 38 which is fixed on the inner end of the shaft 30, and the interior of which is flared toward and open at the outer end. Extending longitudinally through the shaft 30, which is hollow for this purpose, is an elongated fuel supply tube 39. A nozzle 40 is mounted on the outlet end of the tube 39 within the atomizer cup 38. The other end of the tube 39 is fixed in the valve body 35, and in communication with a passage 41 adapted to be connected by a throttle valve 42 to a tube 43 leading from a pump (not shown). The pump has a drive shaft 44 which extends transversely of the shaft 30 into the gear chamber 33 for a drive connection with the motor 36. In the present instance, the shafts are connected by a worm 45 and worm wheel 46, and the latter dips into a lubricant in the bottom of the chamber 33. The air shutter 16 and the fuel valve 42 are interconnected for joint operation from a single actuator 42a which may be operated manually. To this end, the rod 17 is pivotally connected to one arm of a bell-crank lever 47 pivoted on the housing 10. The other arm of the lever 47 is connected by a rod 48 to a crank arm 49 on the plug of the valve 42. A turnbuckle 50 is interposed in the rod 48 and affords means for adjusting the ratio of low pressure air to fuel.

To insure an intimate fuel mixture and fine atomization of the fuel, two sets of peripherally spaced helical vanes 51 and 52 are disposed respectively in the annular low pressure and high pressure air discharge passages. These sets of vanes are oppositely inclined and rigid respectively with the nozzles 8 and 18. Nozzles with vanes of different inclination may be substituted depending on the nature of the flame desired. Thus, the flame may be long and narrow or short and wide. The vanes are so orientated that, assuming the cup 38 as rotating clockwise, the high pressure primary air is discharged counterclockwise, and the low pressure secondary air is discharged clockwise.

The oil burner with the specific features of the nozzle structure herein disclosed, but independent of the air and fuel regulating means and of details of the air supply means, is claimed in my copending application Serial No. 150,279, filed

June 25, 1937.

In operation, air enters the housing 25 through the openings 26, 27 and 28, cools the motor 36, and passes to the blower 11. It is discharged into the housing 10, and passes from there in part to the nozzle 8 and in part to the blower 21. The

air from the blower 21 passes to the nozzle 18. Fuel is supplied through the valve 42 and the tube 39 to the nozzle 40 from which it is discharged into the revolving atomizing cup 38. The fuel and air are intimately mixed. When the flame is turned down, the shutter 16 is adjusted to reduce the volume of low pressure secondary air, but the full supply of primary air is maintained. As a result, the flame is never lazy or smoky, and a high efficiency is always maintained.

I claim as my invention:

1. In an oil burner, in combination, a secondary air nozzle, a secondary air housing in communication with said nozzle, a primary air nozzle coaxially associated with said secondary air nozzle, a high pressure low capacity blower in said housing for discharging air to said primary air nozzle and having an inlet open to the interior of said housing, a fuel nozzle extending into said primary air nozzle, a low pressure high capacity blower mounted in and discharging air to said housing and having an atmospheric air inlet, said first mentioned blower having relatively long and narrow blades with a relatively large external circle of revolution and said second mentioned blower having relatively short and broad blades with a relatively small external circle of revolution, and a drive shaft for said blowers extending axially of said nozzles.

2. An oil burner comprising, in combination, associated primary and secondary air nozzles, a fuel nozzle associated with said primary air nozzle, a high pressure blower for supplying air to said primary air nozzle, a low pressure blower for supplying air to said high pressure blower and to said secondary air nozzle, means for supplying fuel to said fuel nozzle, means for regulating the fuel supply, means for regulating the supply of secondary air from said low pressure blower to said secondary air nozzle, and manually operable means interconnecting the fuel supply regulating means and the secondary air supply regulating means for joint operation, whereby an increase in the fuel supplied will be accompanied by a corresponding increase in the supply of secondary air.

3. In an oil burner, in combination, an external secondary air housing having an atmospheric air inlet in one side and an aligned secondary air outlet in the other side, a secondary air nozzle connected to said housing and communicating with said outlet, an internal air housing rigidly mounted within said external housing and in spaced relation thereto and having an air inlet in one side opening from said external housing and an aligned primary air outlet in the other side, a primary air nozzle mounted in said external housing and communicating with said primary air outlet and extending in concentrically spaced relation through said secondary nozzle, a drive shaft extending coaxially through said housings, a rotary propeller having a closed end disk fixed on said shaft in axially spaced relation to said internal housing and having a plurality of short wide vanes with a relatively small external circle of revolution in annularly spaced relation on the side of said disk remote from said internal housing, the inner ends of said vanes extending partially across said first mentioned inlet, air from the periphery of said propeller being directed by said external housing about said internal housing to said first mentioned outlet, means for directing air from the periphery of said propeller radially inwardly to said second

- mentioned inlet, a second propeller having a closed end disk fixed on said shaft within said internal housing and having a plurality of angularly arranged narrow long vanes of a relatively large external circle of revolution on one side of said last mentioned disk, the inner ends of said last mentioned vanes extending partially across said second mentioned inlet, air from the periphery of said second mentioned propeller being directed by said internal housing radially inwardly to said second mentioned outlet, means for supplying fuel oil axially through said shaft and including a fuel nozzle for discharging fuel through said primary air nozzle, and means for rotating said shaft.
4. An oil burner comprising, in combination, primary and secondary air nozzles, a fuel nozzle extending into said primary air nozzle, means for supplying high pressure air to said primary nozzle and low pressure air to said secondary air nozzle, means for supplying fuel oil to said fuel nozzle, means for regulating the fuel supply, means for regulating the volume of air supplied to said secondary air nozzle, and means interconnecting said last two mentioned means for joint synchronous operation, whereby an increase in the fuel supplied will be accompanied by a proportional increase in the supply of secondary air.
5. An oil burner comprising, in combination, primary and secondary air nozzles, a fuel nozzle
- extending into said primary air nozzle, means for supplying high pressure air to said primary air nozzle and low pressure air to said secondary air nozzle, means for supplying fuel oil to said fuel nozzle, means for regulating the fuel supply, means for regulating the volume of secondary air, and means interconnecting said last two mentioned means for joint synchronous operation, whereby an increase in the fuel supplied will be accompanied by a proportional increase in the supply of secondary air.
6. An oil burner comprising, in combination, primary and secondary air nozzles concentrically mounted to discharge coaxially into a furnace, a fuel nozzle extending into said primary air nozzle, means including a quantity regulating means for supplying fuel oil to said fuel nozzle, a high pressure blower for supplying air to said primary nozzle, a low pressure blower for supplying air to said secondary air nozzle, a damper interposed between said low pressure blower and said secondary air nozzle for controlling the supply of air to said secondary air nozzle, and means interconnecting said regulating means and said damper, said last mentioned means being manipulable for joint operation of said regulating means and said damper and being adjustable as to its length to vary the ratio of secondary air to fuel oil.
